UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,160,173.

Specification of Letters Patent. Patented Nov. 16, 1915.

Original application filed May 26, 1909, Serial No. 498,425. Divided and this application filed December 11, 1912. Serial No. 736,176.

To all whom it may concern:

Be it known that I, HARRY J. HICK, a citizen of the United States, residing at Alliance, in the county of Stark and State of Ohio, have invented certain new and useful Improvements in and Relating to Filing Appliances, of which the following is a specification.

This invention relates to filing appliances, 10 ordinarily known as credit accounting appliances, it being more particularly adapted for the systematic filing and keeping of memoranda, data, slips of paper and the like, incident to business systems, such as 15 sales slips, bills or accounts payable and receivable, statements, ledger cards and for similar purposes.

This application is a division of my application filed May 26, 1909, Serial No. 498,425, 20 issued February 4, 1913, in Patent No. 1,052,444.

One object of the invention is to provide in a filing appliance, having one or more filing sections provided with a slip-holding 25 clip or series of clips, a separating plate or divider forming on the filing section a pocket or pockets adapted to receive and hold memoranda and records, such as bills payable or receivable, statements, and other 30 data and records.

Further objects of the invention consist in the combination or combinations of parts described and claimed in the following specification, reference being had to the accompanying drawings illustrating one form of 35 the invention.

Figure 1 is a perspective view of a filing appliance embodying my invention, most of the leaves of the series of leaves being reclined, and the casing or housing being broken away. Fig. 2 is a fragmentary view of the upper portion of the leaves when in normal vertical position. Fig. 3 is a sectional view of one of the leaves. Fig. 4 is a 40 modification of one of the leaves. Fig. 5 is a fragmentary detail view on the line 7—7 of Fig. 4. Fig. 6 is a fragmentary view of a portion of the casing and leaves, when the latter are in normal position. Fig. 7 is a 45 fragmentary view in perspective showing 50

one of the separator plates. Fig. 8 is a fragmentary perspective view of the modified form of the invention illustrated in Fig. 4.

In the drawings, 1 indicates a casing or housing of any usual or preferred construction. It preferably comprises an upright portion 2, having a back 2^a and side pieces 2^b, 2^c, and a desk portion 3, having a transparent top 3^a, an index carrying slide 3^b, and drawers 3^c, 3^d, the latter being adapted to receive and store blanks, pads, pad holders, pencils, or other supplies and articles for use in carrying out the system, if desired. 55

4 indicates a support, preferably arranged on a level with or slightly above the desk 60 top 3^a.

5 indicates a plurality of leaves or sections, the front one 5^a being, in the example illustrated, pivotally mounted at 5', 5', on the support 4. 70

Preferably, suitable pivoting and connecting devices 6 are arranged between the leaves or sections, so that when one or more of them are reclined from the vertical, the lower edges of all the remaining upright 75 leaves or sections move forward to the position occupied by the lower edge of the last leaf reclined. It will be understood that the series of leaves 5 may be pivotally mounted in any desired manner. 80

7 indicates a series of record or bill-holding spring operated clips mounted upon one or both sides of each leaf or section, as desired.

7' indicates one form of clip shown on 85 some of the leaves, and 7² indicates another form of clip on other leaves 5.

Each of the clips 7 is preferably formed from resilient wire, and coiled at 7^a near its opposite ends to form springs for normally 90 pressing the clip toward the adjacent face of the leaf. The free ends of the wire are suitably secured to the leaves 5. It will be understood that my invention is not limited to a spring clip, as any suitable bill-holding 95 clip or clamp may be employed. They are preferably of skeleton form in order that the memoranda or the slips or papers filed behind them can be easily read.

5^a' indicates a plurality of spacing strips 100

extending longitudinally of each leaf and parallel to each other. The strips 5^a operate to strengthen the leaves, as well as to space them apart, and to form side walls for 5 each slip filing section.

8 indicates a separating plate or divider for some of the leaves or sections, preferably arranged behind one or more of the clips 7² and adapted to be engaged and normally 10 pressed by said clip or clips against the adjacent face of the leaf or section 5. The separating plate 8 preferably comprises a metallic plate 8' that forms a backing against which the clip or clips 7 act. The 15 plate 8' is pivoted on or near the axis of the clips 7 relatively to the face of the adjacent leaf or section 5. Preferably the pivoting means for the separating plate comprise pins 8^a, 8^a, arranged near opposite ends thereof. 20 Each pin 8^a extends laterally from the end of the plate and has bearing in the adjacent coil 7^a. Each plate 8 may be bent to provide an inwardly projecting flange 8^b along its lower edge which serves as a rest for the 25 papers filed behind the plate.

The purpose of the separating plate is to provide convenient means for the systematic filing and keeping in a single appliance of notes, bills payable or receivable, accounts 30 payable, inventory records, agreements and other memoranda, preferably concealed from view, as well as all memoranda relating to each separate account, and which it may be desirable to formulate and record from time 35 to time for ready inspection and reference.

As will be understood from the drawings the divider or separator 8 consists of a plate, which is preferably formed from sheet metal, and of a size to fit between adjacent 40 strips 5^a. The divider thus serves to conceal from view any and all papers filed behind it. It will therefore be seen that each filing section may be provided with two slip holding members, one of which is of skeleton 45 form and permits the memoranda on the last filed slip or paper to be clearly seen and read, and the other of which entirely conceals from view those papers filed behind it.

50 For convenience in operation, I preferably arrange the upper edges of the leaves 5 adapted to receive the credit sales slips, in echelon, so that the index devices 11 may be readily seen. As the leaves provided 55 with separating plates 8 are not intended to be used generally, their upper edges are shown in the drawings as being arranged in the same horizontal plane, one behind the other. The upper edges of these last mentioned leaves may, however, be arranged in echelon, if desired.

12 indicates a guiding device. This device preferably comprises an arm pivoted to the back 2^a and provided with a latch 12^a

at or near its free end. The guide arm 12 is 65 gravity operated and when all the leaves are in normal vertical position its catch 12^a engages the upper edge of the front leaf 5^a and holds all the leaves closed. When the front leaf 5^a is reclined, the guide arm 12 is 70 moved upwardly into the position shown in Fig. 1, against a stop 12^b and operates then to move the upper edges of all the upright leaves forward when one or more of them are reclined. If all the leaves except the 75 last leaf of the series is reclined, the upper edge of the last leaf engages with the catch 12^a and is held upright thereby. When the upper edges of some of the leaves are arranged in the same horizontal plane, one behind the other, and the other leaves of the 80 series are arranged in echelon, as shown in the drawings, the guide arm 12 is bent, as shown at 12^c, so that it will lie in the same plane with the upper edges of all of the 85 leaves.

In Figs. 4 and 8 I have illustrated one modification of the invention. Referring to such view, 13 indicates a separating plate or divider arranged behind and common to 90 a plurality of adjoining clips 7³, 7³. In the preferred form of the construction a separator plate is arranged behind and common to each two adjoining clips 7³, 7³. 14 indicates pivot pins loosely mounted at 95 the lower edge of the separator plates 13 and each arranged to have its opposite ends extend into the adjacent coils 7⁴ of the springs 7³ and be pivoted thereto relatively to the adjacent leaf face.

In order to provide compensating means for the memoranda and data to be filed behind the separator 13, the pins 14 are bent at substantially right angles at 14^a, 14^b, 14^c. 14^a, to form an off-set portion 15 which is 105 loosely pivoted to the lower edge of the separator 13. This construction permits the lower edge of the separator to accommodate itself to the thickness of the papers or memoranda filed behind the separator 13, whereby the papers or memoranda may be filed one behind the other and held in perfect order by the separator 13.

To those skilled in the art of making apparatus of the class described, many alterations and widely differing embodiments and applications of my invention will suggest themselves. My disclosures and description herein are purely illustrative, and are not intended to be in any sense limiting.

For the purpose of illustrating a use to which the leaves or sections provided with separators or dividers are adapted, I have shown in Fig. 4 one of the dividers broken away to expose an account 16 of John Jones 115 against the proprietor of the appliance, William Smith. It should be assumed that another or additional and later account 120

payable between the same parties is rendered. The first one is numbered 1, and the amount is for \$500.00. When it was received, a slip 17 was made out in the name 5 of John Jones, carrying the amount of account No. 1 and placed under the clip 7³ and number 16, which index number designates John Jones' filing section in the appliance. When the second account is received, it is numbered 2, and a second clip 10 17 is made out in favor of John Jones and having carried forward on it the amount \$500.00 of the first slip, to which is added the amount of \$700.00 of the second slip, 15 giving a total of \$1,200.00 on the second slip, which slip may then be filed under the clip 16. Now the advantage of this system is due to the fact that the slips may be made in multiple and in such manner that 20 one may be filed under John Jones to show the amount owed him to date, the other may be filed under a section devoted to total accounts payable, the amount of John Jones' last bill being added to the amount of total 25 accounts payable on the last slip appearing in the section devoted to that purpose; the third slip may be used in the stock account to show the amount of stock on hand; and the fourth slip may be used for taking advantage of the last day for discounting the 30 last bill rendered, etc.

The advantage of the appliance for accommodating such a system of keeping a merchant's record will be at once apparent. 35 The bills payable, accounts payable, and the like, may be filed systematically and concealed from view by the separators or dividing plates, simply indexed for reference purposes, and manifolding pads may be employed, the slips of which filled in at a single writing, may be used for keeping up to date various details of the merchant's business, among others, the total amount of all the accounts payable owed a particular 40 party, which slip when made out is filed under the spring clip which bears upon the separator or dividing plate behind which are filed the accounts payable of the creditor in question, or a ledger sheet in card 45 form or other form may be used for keeping a record of debits and credits of any account and it may be held by the spring clip above mentioned.

What I claim is:

55 1. The combination of a series of leaves, means permitting said leaves to swing relative to each other, a skeleton paper-engaging spring clip carried by each leaf, a plate interposed between one of said clips and the 60 adjacent leaf, and means for pivotally supporting said plate loosely relative to said leaf on an axis substantially coincident with the axis of the clip and permitting it to swing independently of said clip.

2. The combination of a series of leaves, 65 means permitting said leaves to swing relative to each other, a spring clip carried by each leaf, a supporting plate interposed between one of said clips and the adjacent leaf, and means for pivotally supporting 70 said plate loosely relative to said leaf on an axis substantially coincident with the axis of the clip and permitting it to swing independently of said clip, the said plate being provided with a flange which serves as a 75 rest for the papers filed behind it.

3. The combination with a swingable leaf, of a pair of devices for holding papers on said leaf, and means for pivotally supporting said devices on said leaf on the same axis 80 but to move independently of each other, one of said devices comprising a wire clip having coils for operating it toward the leaf and permitting the papers filed behind it to be inspected without removal and the other device comprising a plate that is pressed toward said leaf by the clip and serves to conceal from view the papers filed behind it. 85

4. The combination of a leaf or frame, a support therefor, a plurality of independently operated spring clips carried thereby, a separator common to and arranged between said clips and said leaf, and means for pivotally supporting said separator relative to said leaf and permitting it to swing 90 independently of the clips, the said clips operating independently to press the separator toward the said leaf. 95

5. The combination of a swingable leaf for a filing appliance, of a paper supporting 100 device comprising a plate provided with a flange extending from its lower edge inwardly and serving as a rest for papers, and means tending to press the upper edge of said plate toward said leaf. 105

6. In a filing appliance, the combination of a series of pivotally mounted leaves, each provided with a plurality of spring operated paper engaging clips, and a paper supporting plate interposed between one of said 110 spring operated clips and the face of an adjacent leaf, and means for loosely pivotally supporting the plate on substantially the same axis as the axis of the clip. 115

7. In a filing appliance the combination of a movable leaf or frame, a support therefor, a plurality of independently operable spring clips carried by said leaf or frame, and a separator pivotally mounted relative to said leaf or frame and arranged between it and the clips and swingable independently thereof. 120

8. In a filing appliance, the combination of a series of pivotally mounted leaves, each provided with a plurality of independently operable spring clips, and means comprising a pivoted plate common to and acted upon by each of the clips and pivoted relatively 125

- to the adjacent leaf, for holding memoranda relating to the records exposed beneath either of said clips. 60
9. In a filing appliance, the combination 5 of a series of pivotally mounted leaves arranged to be assembled face to face, paper engaging clips carried by each of the leaves and each provided with coiled springs for normally operating the said clips, a paper 10 supporting plate arranged behind one or more clips and normally pressed against the face of an adjoining leaf, and means for hinging the said plate in the said spring coils, and permitting it to swing independently of the adjacent clip. 15
10. In a filing appliance, the combination with a series of pivotally mounted leaves, arranged to be assembled face to face, a plurality of paper engaging clips on one or 20 both faces of each of the said leaves and each provided with a pair of coiled springs adapted to press the said clips toward the face of an adjacent leaf, a paper supporting plate forming receiving pockets interposed 25 between each clip and the face of an adjacent leaf, and pivot pins carried by each plate having their free ends extending into the coils of the said springs to permit the plate to swing relatively to the said leaf 30 independently of the adjacent clip. 35
11. In a filing appliance, the combination of a leaf or frame, a plate for supporting and holding memoranda, a spring operated clip for receiving records and arranged 35 to normally press the plate against the face of the leaf, devices for pivotally supporting the plate, provided with means for permitting the plate to accommodate itself to the thickness of the memoranda papers. 40
12. In a filing appliance, the combination of a support, a leaf or frame pivotally mounted thereon, and provided with a plurality of clips, a plate for supporting and holding papers pivoted relative to said leaf 45 or frame and arranged between one of said clips and the adjacent face of the leaf or frame, said plate being provided with an inturned lower edge on which the papers filed behind it are supported and means for 50 pivotally supporting said plate and permitting it to accommodate itself to the papers filed behind it. 55
13. In a filing appliance, the combination of a leaf or frame, a separator plate, a clip arranged in front of said separator plate and movable relative thereto to receive memoranda between the separator plate and the clip, and arranged to press the separator plate against the adjacent face of the leaf, 60
- and a pivot pin for swingably supporting the separator plate relative to the leaf and having an off-set portion loosely connected to said separator plate. 65
14. In a filing appliance, the combination of a leaf, a separator plate for holding memoranda, a clip arranged in front of said separator plate adapted to receive and hold records and to normally press the separator plate against the face of the leaf, coiled springs for operating the clip, and a pivot 70 pin for swingably supporting the separator plate, the said pivot pin having its free ends extending into the coils of the said springs and loosely supported thereby and being formed with an off-set portion loosely pivoted to the said separator plate to permit the latter to accommodate itself to the thickness of the memoranda concealed by the said separator plate. 75
15. In a filing appliance, the combination 80 of a leaf, a series of paper engaging spring clips carried by said leaf and arranged side by side to swing independently on axes coincident with each other, a paper supporting plate carried by said leaf and arranged 85 behind two adjoining spring clips thereon, and means for pivotally supporting the plate to swing on an axis substantially coincident with the axes of the adjacent clips and independently thereof. 90
16. A file clamp mechanism, comprising a supporting base, a hinge pin mounted on said base, a hinged plate mounted on said hinge pin, its hinge engaging portion being of less width than the width of said plate, 95 a coil spring mounted on said hinge pin on either side of the hinge engaging portion of said plate, and a loop formed by the continuation of the internal ends of said coil spring bearing upon and forming clamping 100 means on the exterior surface of said plate. 105
17. A file clamp mechanism, comprising a supporting member, a hinge pin mounted on said member, a hinged plate member, engaging said hinge pin and pivotally supported thereon, and a spring engaging said hinge pin and forming a clamping member to engage a memorandum supported on said plate member, whereby substantially the entire area of the plate is exposed for writing 110 on the memorandum sheet held on said plate.

In testimony whereof I affix my signature, in the presence of two witnesses.

HARRY J. HICK.
